ATTORNEY.

UNITED STATES PATENT OFFICE

ALAN VARLEY LIVINGSTON, OF NEW HAVEN, CONNECTICUT, ASSIGNOR TO THE SAFETY CAR HEATING & LIGHTING COMPANY, A CORPORATION OF NEW JERSEY

REGULATING APPARATUS

Application filed May 28, 1928. Serial No. 112,219.

This invention relates to electrical systems of distribution and more particularly to car lighting systems in which the generator may be driven, for example, from a car axle.

One of the objects of this invention is to provide a system of the above-mentioned character in which apparatus of simple construction and of thoroughly dependable action may be employed for efficiently and dependably safeguarding the system and translating devices associated therewith against changes in the electrical conditions. Another object is to provide a system of the above-mentioned character which will be of thoroughly dependable action and well adapted to meet the widely varying conditions of practical use. Another object is to provide a regulator in which is included a variable resistance preferably in the form of a compressible carbon pile, which will be of simple construction and highly sensitive action. Another object is to provide a regulator of the above-mentioned nature capable of rapid and powerful response to the variations or changes in the electrical conditions which it is adapted to rectify, and to achieve these objects in a thoroughly practical way and with simple and dependable apparatus. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which are shown several of the possible embodiments of my invention,

Figure 1 is a diagrammatic representation of the circuit arrangements and of the apparatus illustrative of certain features of my invention as embodied in a car lighting system, and

Figure 2 is a like representation of a modified and preferred form of system and apparatus.

Similar reference characters refer to sim-

ilar parts throughout the several views of the drawing.

Referring now to the drawing and more particularly to Figure 1, there is shown at 10 a generator adapted to be driven, in a car lighting system, from a car axle, for example; the generator 10 may be of the shunt wound type and is provided with a shunt field 11 supplied with exciting current through a variable resistance preferably taking the form of a compressible carbon pile 12. The generator 10 is connected to the main line conductors 13 and 14 and may supply energy to a storage battery 15 and to lamps 16, an automatic switch generally indicated at 17 being provided for connecting the generator to the battery and lamps when the voltage of the generator reaches a predetermined value and for disconnecting the generator therefrom when the voltage drops to a predetermined value. This automatic switch 17 may take any suitable or appropriate form. Preferably also, there is interposed between the battery 15 and the lamps 16 a regulator generally indicated at 18; this regulator 18 may also take any suitable or appropriate form, and is adapted to maintain substantially constant the voltage across the lamps 16 throughout such changes in voltage across the battery 15 as are due to the change in the state of charge of the battery or as are due to such conditions as depend upon whether the battery is being charged or not.

Operative upon the carbon pile 12 is a lever 19 pivoted as at 20 and at substantially like distances from the pivot point 20, there are connected to the lever 19 the cores 21 and 22 of two solenoids; the lever 19 is provided with an arm 23 for engaging the movable end of the carbon pile 12, and the lever 19 with its associated solenoid cores is preferably so arranged as to form a substantially balanced mechanical system. In order, however, to maintain the carbon pile 12 under some degree of compression when the generator 10 is at rest or starting up, the mechanical system operative upon the carbon pile 12 is preferably somewhat out of balance, and such an out of balance condition may be

achieved by means of a weight 24 attached to the lever 19 and at such a position as to tend to compress the carbon pile 12.

Operative upon the cores 21 and 22 are appropriate windings arranged to be responsive to those electrical changes in the system which are intended to be rectified, and by way of illustration, the windings are shown as being responsive to changes in the voltage. About the core 22 are two windings 25 and 26, adapted to coact one with the other and about the core 21 is a winding 27. At this point it might be noted that the solenoids are preferably so constructed and designed as to give a substantially constant pull at the normal voltage and in all positions of the movable core throughout the operating range of the latter.

The windings 25 and 27 are preferably connected in series with each other but through a variable resistance 28 and the filament 29 of a thermionic device 30, preferably of the two-element type, and having an appropriate anode or plate 31 coacting with the other cathode 29. The circuit of the windings 25 and 27 will thus be seen to be as follows:—From one side of the generator 10, as from the main line conductor 14, then conductor 32, filament 29, adjustable resistance 28, winding 25, conductor 33, winding 27, conductor 34 and thence to the other main line conductor 13 and hence to the other side of the generator 10. Changes in voltage of the system, therefore, will affect in like degree the heating of the filament cathode 29 and also the energization of windings 25 and 27 of the two solenoids, the latter acting, as will be clear, in opposition to each other.

The circuit of the winding 26, which acts with the winding 25, upon the core 22, is included in the plate circuit of the thermionic device 30 and will be seen to be substantially as follows:—From one terminal of winding 26, adjustable resistance 28, cathode 29, thence through the available electron path of the device 30 to the plate 31, conductor 35, secondary winding 36 of an appropriate transformer, and thence to the terminal of the coil 26. A condenser 37, bridged across the coil 26 acts to smooth out the half-waves of the current flowing in the plate circuit due to the appropriately high alternating potential supplied in the plate circuit by the secondary winding 36 of the transformer.

The primary winding 37 of the transformer 36—37 is connected by conductors 38 and 39 to a suitable source of alternating current. This source may take the form of a converter or motor-generator operated from the main line conductors of the system, as will be made more clear hereinafter in connection with Figure 2, or it may take the form of the armature of the generator 10 itself, it being understood that the armature windings of the generator 10 may be con-

nected appropriately and to suitable slip rings 40 to supply the appropriate alternating potential.

Considering now the operation of the system and the apparatus, it may first of all be pointed out that, if desired, any suitable means may be provided to maintain the current output of the generator substantially constant during the charging of the storage battery 15; as the latter approaches substantially full charge, however, its back e. m. f. rises substantially rapidly so that, if the generator voltage is thereupon kept at an appropriate relatively constant value, the charging current to the battery will taper off and the battery thus safeguarded against over-charge. It is at such an appropriate voltage that the regulating apparatus illustratively shown in Figure 1 is adapted to maintain substantial constancy against the speed changes of the generator 10, as well as to maintain such relatively constant voltage against whatever changing conditions in the system may tend to bring about a departure thereof. And, as illustratively shown in Figure 1, the apparatus will maintain the generator voltage substantially constant and preferably at a value such that, as the battery 15 approaches substantially full charge, the back voltage of the latter approaches or equals the voltage maintained constant by the regulator so that the battery is protected against overcharge.

The windings 25 and 26 operative upon the core 22 are adapted and designed so that, at the desired voltage, the ampere turns provided thereby and thus the pull exerted thereby upon the core 22 substantially equal the ampere turns provided by the winding 27 and corresponding pull exerted thereby upon the core 21, respectively. When, therefore, the voltage of the generator is at the desired value, the forces active upon the cores 21 and 22 are substantially equal to each other, due provision being made for compensating for the effect of the weight 24, and the lever 19 will be maintained in equilibrium and the pressure upon the carbon pile 12 held at a corresponding value. Likewise, at this intended voltage, the filament 29 will be heated to an appropriate and operative degree, and preferably at such a value that the thermionic device 30 may be made to operate throughout that portion of its operating characteristic which is below the saturation point or below the knee of the characteristic. The adjustable resistance 28 may be utilized to adjust the several parts in order to bring about the conditions above-mentioned.

The winding 25 is preferably proportioned with respect to the winding 26 so that the former contributes about 75% of the necessary ampere turns for operation upon the core 22; this relation of the coils 25 and 26, however, may be varied throughout a wide

extent, as may be desired, and furthermore, if desired, the coil 25 may be entirely omitted and the coil 26 adapted and designed to supply the ampere turns necessary for action 5 upon the core 22.

Assuming, however, that a change in the voltage of the system takes place, due, for example, to a change in the speed of the generator 10, and assuming, furthermore, that 10 the voltage increases, the energization of the solenoid 21-27 will be correspondingly increased, but a part of the thus increased pull exerted by the winding 27 is counteracted by a like increase in the pull exerted 15 by the winding 25 operative upon the core 22. At the same time, however, the same voltage increase causes a corresponding increase in the heating of the cathode 29 of the thermionic device 30, so that the conductivity of the electron path between the two electrodes of the device 30 becomes increased but in a disproportionately greater degree; also the voltage increase is effective 20 to increase the alternating potential supplied 25 by the slip rings 40 and thus to increase in substantially like degree the potential effective in the plate circuit of the thermionic device 30. These changes in heating of the filament 29 and in the potential of the anode 30 31, each substantially directly proportional to the change in the voltage, bring about, however, due to the characteristics of the thermionic device 30 and due to the portions 35 of the characteristics of the latter throughout which the device 30 is operated, a disproportionately greater increase in the energization of the winding 26. The ampere turns thus effective on the core 22 are made 40 to relatively greatly preponderate over the ampere turns effective in the winding 27 upon the core 21, so that there is promptly exerted 45 a powerful movement of the lever 29 in a clockwise direction about its pivot 20, thereupon to relieve the pressure on the pile 12, and by correspondingly increasing the resistance in the circuit of the field winding 11, to bring about a reduction to normal of 50 the voltage of the generator 10. The heating of the cathode 29, the potential of the plate 31, and the energization of the several windings active upon the two cores, are thus 55 brought back to their normal values, the windings, as will be clear from what has been set forth hereinabove, acting, however, to hold their respective cores in the position into which they have been moved.

Should the change in voltage be in the direction of a decrease in the voltage, substantially the reverse action takes place, it being pointed out that the decrease in the heating of the cathode 29, the effect of which 60 may be and preferably is supplemented by a corresponding decrease in the potential of the plate 31, is made, by virtue of the characteristic 65 of the thermionic device 30, to rapidly

diminish the energization of the winding 26 operative upon the core 22 but to a much greater extent than is the corresponding decrease in the energization of the winding 27 operative upon the core 21. The solenoid 21-27 is thus quickly made effective to become powerfully effective to increase the pressure upon the carbon pile 12, and thus to effect a corresponding rapid increase and restoration to normal of the voltage of the 70 generator 10.

It will thus be seen that, while, when normal electrical conditions are prevailing in the system, the two opposing solenoids are substantially equal in their opposing effects and maintain the mechanical system in a state of equilibrium, yet the occurrence of a departure from the normal or desired electrical conditions is made to bring about a rapid and powerful preponderance of one 80 of the opposing solenoids over the other. A high degree of sensitivity is thus achieved, and this as well as many other advantages, is achieved, together with the very important advantage of having the two solenoids electrically, magnetically and mechanically of 85 substantially identical construction. Furthermore, also temperature compensating resistances need not be employed since, irrespective of whatever temperature changes 90 may be balanced out by reason of the windings 25 and 27 being in the same circuit, differences in action of the two solenoids due to differences in temperature become substantially immaterial because of the disproportionately greater response of the thermionic device 30 to a given increment of 95 change in the electrical conditions in the system.

Referring now to Figure 2, it may first be noted that the coil 27 operative upon the core 21 is connected by conductors 41 and 42 directly across the storage battery 15, so as to be energized by the latter when the generator 10 is at rest or operating at such 100 a speed that the main switch 17 is open. The solenoid 21-27 may thus act to maintain the carbon pile 12 under substantial degree of compression under the conditions 105 pointed out above, thereby avoiding the use of a device such as the weight 24 of Figure 1 and permitting the mechanical system of the regulator of Figure 2 to be substantially 110 perfectly balanced; thus the picking up of the generator promptly is at all times insured, while as soon as the main switch 17 is closed, the coil 27 is electrically positioned to be responsive to voltage changes so that 115 its action may be substantially similar to the coil 27 hereinbefore described in connection with Figure 1.

In the arrangement of Figure 2, the primary winding of the transformer 36-37 is supplied with an alternating potential of 120 suitable value by means of the motor gener- 125

ator or converter generally indicated at 43 and adapted to be supplied with energy from the main line conductors 13 and 14, to which it is connected by the conductors 44 and 45 respectively, though it will be understood that the main generator 10 may be made, as illustratively shown and described in connection with Figure 1, to supply the appropriate alternating potential. The winding 10 25, which coacts with the winding 26, with respect to the core 22 at the opposing end of the lever 19, will be seen to be connected to be responsive to the changes in the electrical conditions of the system, illustratively 15 set forth as voltage changes. The circuit of the winding 25 will be seen to lead from one side of the generator 10, as the main line conductor 14, thence through conductor 32, filament cathode 29 and thermionic device 30, 20 adjusting resistance 28, winding 25 and thence by way of conductor 46 to the main line conductor 13 and hence to the other side of the generator.

The operation of the apparatus and system of Figure 2 will be clear, it is believed, from what has been set forth in detail in connection with Figure 1. It may generally be noted, however, that a change in the voltage of the system from the desired value at 25 which the two solenoids are substantially equally opposed in their effect and maintain the mechanical system operated thereby in substantial equilibrium, causes the rapid and relatively great preponderance of the one 30 over the other due to the peculiar characteristics of the thermionic device 30, so that there is achieved not only highly sensitive response of the regulating apparatus but also a powerful action thereof to bring about 35 rectification of the changes in the electrical conditions of the system. Differences in action or effect of various of the coils or windings of the regulating apparatus of Figure 40 2 need not be compensated for, as is common practice by the inclusion in the respective circuits of relatively high compensating resistances, since the disproportionately greater resultant effect of the thermionic device due to a given increment of change 45 makes such compensation unnecessary. It will furthermore be understood that the strength of the winding 25 with respect to the winding 26 may be proportioned as desired, and that the winding 25 may be omitted if desired. The weaker that the winding 50 25 is made with respect to the winding 26 (in either Figure 1 or Figure 2) the more rapidly and powerfully is the one solenoid 55 made to preponderate over the other. I prefer, however, to include such a winding as the winding 25 for coaction with the thermionic-controlled winding 26 since, in such case, the winding 26 can be supplied with less 60 energy and the thermionic device 30 as well

as the transformer 36-37 may be of less capacity.

It will be understood, however, that if desirable, the resistance 28, hereinabove described in connection with the adjustment 70 or setting of the apparatus, may be constructed or designed to have a temperature compensating action, and that this may be desirable depending upon various practical conditions that may be met with. 75

I wish also to point out that it may, under certain conditions, be desirable to associate with the movable parts of the regulator an appropriate damping device, such as a dash pot, for example, in order to steady 80 the action of the regulator, should such steadyng action be made necessary by the practical conditions of use. And I would also point out that by the rapidity or quickness of action described above in connection 85 with the operation of the regulating apparatus, I mean to include not necessarily a high speed of movement of the movable parts but rather such a rapidity of action as brings about a relatively prompt restoration 90 of the predetermined standards of electrical conditions which it is desired to maintain in the circuit. For example, hysteresis effects, or changes or variability of friction factors in the movable parts of the regulator and like factors oftentimes are the cause of having the regulator maintain a relatively higher or relatively lower standard of regulation with respect to the desired 95 or intended standard, because of the fact 100 that various factors, some of which have been illustratively mentioned above, are of such a nature that it takes the controlling coil or coils relatively long periods of time to overcome these factors and to bring about 105 conditions, either electrical, mechanical or magnetic, necessary to completely restore and maintain the desired or intended standard of regulation. The characteristics of the thermionic device and the coaction of the latter with the regulator, however, insure the prompt overcoming of such factors as have been above-mentioned illustratively and thus 110 a high degree of closeness and accuracy of regulation are ensured. 115

In both Figures 1 and 2, I have shown preferred embodiments of an arrangement for insuring against the failure of the thermionic device; I prefer to associate with the thermionic device 30 as many additional thermionic devices as may be desired, and in the drawing I have shown a single additional thermionic device 48, though it is to be specifically understood that additional ones may be associated with respect to the device 30 120 in substantially the same manner as is the device 48 associated with the device 30 and its respective circuits. 125

Referring, for example, to Figure 2, the thermionic device 48 is provided with a plate 130

anode 49 connected by conductor 50 to the conductor 35; the latter, it will be noted, is connected also to the plate anode 31 of the device 30 and to one terminal of the secondary winding 36 of the transformer 36-37. The filament cathode 51 of the supplementary thermionic device 48 is connected substantially in parallel with the filament cathode 29 of the device 30, but through a relay-switch generally indicated at 52. This relay-switch 52 may be of any suitable construction and is illustratively shown as being of the solenoid type. It is provided with a winding 53 connected by conductors 54 and 32 to the main line conductors 13 and 14 respectively, and on the generator side of the main switch. The relay 52 is also provided with a winding 54 which will be seen to be in circuit with the filament cathode 51 and will thus be seen to be energized only when the relay 52 has its switch contacts closed. The winding 53 and its associated movable parts of the relay are so designed that, at the maintenance of the normal electrical conditions in the circuit, illustratively shown herein as the maintenance of a predetermined voltage, the winding 53 is insufficiently energized to cause the closure of the switch contacts of the relay 52. The thermionic device 48 is thus maintained ineffective as long as the thermionic device 30 and its associated parts are operative to maintain the desired electrical conditions in the circuit. Assuming, however, that the thermionic device 30 becomes inoperative, as by way of the filament cathode 29 burning out, for example, then the electrical conditions in the circuit become abnormal and illustratively the voltage of the system will begin to rise, due to the failure of an adequate current flow through the winding 26 in circuit with the thermionic device 30.

Upon a predetermined rise in the voltage, the coil 53 becomes sufficiently energized to close the switch contacts of the relay 52 so that the filament 51 of the thermionic device 48 becomes heated, the resultant current flow thereto and through the coil 54 acting by way of the latter to assist the coil 53 in holding the relay contacts closed. The thermionic device 48 is thus substituted for the ineffective or inoperative device 30, and the temporary abnormality in the electrical conditions is promptly eliminated and the regulation of the system may thereupon proceed as will be clear from what has hereinbefore been described in connection with both Figures 1 and 2. The system and apparatus are thus safeguarded against failure of the thermionic device.

It will thus be seen that there has been provided in this invention a system and apparatus in which the various objects hereinbefore set forth, together with many thoroughly practical advantages are successfully

achieved. It will be seen that the apparatus is of simple and thoroughly practical construction, is capable of inexpensive manufacture, and is characterized by highly sensitive and powerful but efficient action when in use. Moreover, it will be seen that the apparatus and system may be readily adjusted to meet varying conditions of practical use.

As many possible embodiments may be made of the above invention, and as many changes might be made in the embodiment above set forth, it is to be understood that all matter hereinbefore set forth or shown in the accompanying drawings is to be interpreted as illustrative and not in a limiting sense.

I claim as my invention:

1. In a system of the character described, in combination, a generator and a carbon pile regulator for controlling the output of said generator, and means for controlling said carbon pile regulator, said means including two solenoids acting in opposition to each other and connected to be responsive to substantially the same changes in a function of the output of the generator, and a thermionic device adapted to cause one of said solenoids to be responsive in greater degree than the other of said solenoids.

2. In a system of the character described, in combination, a generator and a carbon pile regulator therefor; a thermionic device; means for controlling said regulator, said means including a solenoid connected to be responsive to a change in a function of the output of said generator and a second solenoid, acting in opposition to the first-mentioned solenoid, said first-mentioned solenoid being connected in a circuit in which is included the plate anode of a thermionic device, the filament cathode of which is connected to be responsive to changes in a function of the output of said generator.

3. In apparatus of the character described, in combination, a generator, regulating means therefor adapted to control a function of the output thereof, said means including a thermionic device; a second thermionic device; and means adapted upon said function of the output of said generator reaching a predetermined value to make effective said second thermionic device.

4. In apparatus of the character described, in combination, a generator, regulating means therefor adapted to control a function of the output thereof, said means including a thermionic device; a second thermionic device; each of said devices having electrically heated thermionic-emission means; and means responsive to failure of flow of heating current to the means of one device for initiating flow of heating current to the means of the other device.

5. In apparatus of the character described, in combination, a generator, regulating means

therefor, a thermionic device responsive to a function of the output of said generator for controlling said regulating means, a normally ineffective thermionic device adapted to control said regulating means, and means responsive to an abnormal value of the said function of the output of said generator for making effective said second-mentioned thermionic device.

10 6. In apparatus of the character described, in combination, a generator, regulating means therefor, a plurality of thermionic devices, one of which is normally adapted to affect said regulating means, each of said devices having an anode and an electrically heated cathode, means connecting in parallel the space-current paths between said anodes and said cathodes, and means responsive to ineffective condition of the cathode of said 20 one thermionic device for making effective the cathode of another of said plurality of thermionic devices.

7. In apparatus of the character described, in combination, a generator, regulating means therefor, a thermionic device for controlling said regulating means and having a filament electrode, a second thermionic device, connections for supplying heating current to said filament electrode from said generator, and 30 means operated when the heating current to said filament electrode fails for bringing into action said second-mentioned thermionic device to control said regulating means.

8. In apparatus of the character described, in combination, a generator, regulating means therefor, a plurality of thermionic devices each having an anode and a filament cathode, the anodes of said devices being connected together and in a circuit adapted to affect 40 said regulating means and the filament of one of said devices being connected to receive heating current from said generator, and means adapted upon failure of the filament of said one device to become heated to connect the filament of another of said devices to receive heating current from said generator.

9. In apparatus of the character described, in combination, a generator, regulating means therefor, a coil for affecting said regulating means, and a thermionic device responsive to changes in a function of the output of said generator for controlling the energization of said coil; a second thermionic device normally 55 ineffective, and means for making said second thermionic device effective to control the energization of said coil and operative upon failure of said first thermionic device.

10. In apparatus of the character described, in combination, a generator, regulating means therefor, a coil for affecting said regulating means, and a thermionic device responsive to changes in a function of the output of said generator for controlling the 65 energization of said coil; a second ther-

mionic device normally ineffective, and means including a coil responsive to an abnormal value of said function of the output of said generator for making said second thermionic device effective to affect the energization of 70 said coil.

11. In apparatus of the character described, in combination, a generator, a thermionic device connected to be responsive to a function of the output of said generator for controlling the output of said generator; a second thermionic device, normally ineffective; a switch for connecting said second thermionic device to become effective for controlling the output of said generator; a coil for 80 operating said switch and responsive to an abnormal value of the said function of the output of said generator; and a second coil for holding said switch in operated position upon the restoration to normal value of the said 85 function of the output of said generator.

12. In apparatus of the character described, in combination, a generator, regulating means therefor, a thermionic device connected to be responsive to a function of the output of said generator for controlling said regulating means and having a filament cathode connected to receive heating current; a second device normally ineffective; a switch for connecting said second device to become 95 effective for affecting said regulating means; and a coil responsive to failure of the heating current through said filament cathode for operating said switch.

13. In apparatus of the character described, in combination, a generator, a thermionic device connected to be responsive to a function of the output of said generator for controlling the output thereof and having a filament cathode connected to receive a heating current; a second device normally ineffective and having a filament cathode adapted to receive heating current; a switch for connecting said second device to become effective to affect the output of said generator; a coil responsive to failure of the heating current through the filament cathode of said first device for operating said switch; and a coil responsive to the flow of heating current to the filament cathode of said second device for holding said switch closed.

14. In apparatus of the character described, in combination, a carbon pile regulator, means for controlling the pressure thereon including a solenoid tending to compress said pile and a solenoid tending to relieve compression of said pile, said solenoids being connected to be responsive to the same electrical conditions, and thermionic means for causing one of said solenoids to have a greater effect than the other.

15. In apparatus of the character described, in combination, a carbon pile regulator, means for controlling the pressure thereon including a coil, a thermionic device 130

for affecting said coil and adapted to be connected to be responsive to changes in electrical conditions, a second thermionic device, and means responsive to ineffective condition of said first device for making said second device operative to affect said coil.

16. In apparatus of the character described, in combination, a carbon pile regulator, a lever for affecting the pressure thereon and mechanically substantially balanced, a pair of electromagnetic means having opposing effects upon said lever and connected to be responsive to substantially the same changes in electrical conditions, and ionic conduction means for causing one of said electromagnetic means to have a greater responsiveness than the other to a given change in the said electrical condition.

17. In apparatus of the character described, in combination, a carbon pile regulator, a lever for affecting the pressure thereon and mechanically substantially balanced, a pair of electromagnetic means having opposing effects upon said lever and adapted to be connected to be responsive to the same changes in electrical conditions, each of said means having substantially the same electrical and magnetic characteristics, and thermionic means for causing one of said electromagnetic means to have a greater responsiveness than the other.

18. In apparatus of the character described, in combination, a compressible carbon pile regulator, means for controlling the pressure thereon including a pair of solenoids having opposing effects thereon and adapted to be connected to be responsive to substantially the same changes in electrical conditions, each of said solenoids being constructed to have a substantially constant pull throughout the range of movement of the movable parts thereof for normal energization, and means for causing one of said solenoids to have a greater effect than the other for a given change in the said electrical conditions.

19. In apparatus of the character described, in combination, a carbon pile regulator, means for controlling pressure thereon including a coil, a device having spaced electrodes with an electronic conduction path therebetween for affecting said coil and adapted to be connected to be responsive to changes in electrical conditions, a second device having spaced electrodes with an electronic conduction path therebetween, and means responsive to ineffective condition of said first-mentioned device for making said second-mentioned device operative to affect said coil.

20. In apparatus of the character described, in combination, a source of current, a work circuit supplied therefrom, regulating means for controlling a function of the energy supplied by said source to said work circuit, said regulating means including a

device having spaced electrodes between which electronic conduction is adapted to take place, a second device having spaced electrodes between which electronic conduction is adapted to take place, and means effective upon the substantial failure of one of said devices for making effective the other of said devices.

21. In apparatus of the character described, in combination, a compressible carbon pile regulator, means for controlling the pressure thereon including a pair of solenoids having opposing effects thereon and adapted to be connected to be responsive to substantially the same changes in electrical conditions, each of said solenoids being constructed to have a substantially constant pull throughout the range of movement of the movable parts thereof for normal energization, and means having a pair of spaced electrodes between which ionic conduction takes place for causing one of said solenoids to have a greater effect than the other for a given change in the said electrical conditions.

22. In apparatus of the character described, in combination, a source of current, a work circuit to be supplied therefrom, regulating means for controlling a function of the energy supplied by said source to said work circuit, said regulating means including a thermionic device connected to be responsive to said function and having a filament cathode connected to receive a heat current, a second thermionic device normally ineffective and having a filament cathode adapted to receive heating current, a switch for connecting said second device to coact with said regulating means, a coil responsive to failure of the heating current through the filament cathode of said first device for operating said switch, and a coil responsive to the flow of heating current to the filament cathode of said second device for holding said switch closed.

23. In apparatus of the character described, in combination, a carbon pile regulator, means for controlling pressure thereon including a coil, a device having spaced electrodes with an electronic conduction path therebetween for affecting said coil and adapted to be connected to be responsive to changes in electrical conditions, a second device having spaced electrodes with an electronic conduction path therebetween, a switch for making said second-mentioned device operative to affect said coil, means responsive to ineffective condition of said first-mentioned device for causing actuation of said switch, and means responsive to effective condition of said second-mentioned device for holding said switch in actuated position.

24. In apparatus of the character described, in combination, a source of current,

a work circuit supplied therefrom, regulating means for controlling a function of the energy supplied by said source to said work circuit, said regulating means including a device having spaced electrodes between which electronic conduction is adapted to take place, a second device having spaced electrodes between which electronic conduction is adapted to take place, circuit-controlling means adapted to cause said second device to take part in the regulation of said function of the energy from said source, and means responsive to a predetermined value of said function of the energy of said source for causing actuation of said circuit-controlling means.

25. In apparatus of the character described, in combination, a source of current, a work circuit supplied therefrom, regulating means for controlling a function of the energy supplied by said source to said work circuit, said regulating means including a device having spaced electrodes between which electronic conduction is adapted to take place, a second device having spaced electrodes between which electronic conduction is adapted to take place, circuit-controlling means adapted to cause said second device to take part in the regulation of said function of the energy from said source, means responsive to a predetermined value of said function of the energy of said source for causing actuation of said circuit-controlling means, and means responsive to effective condition of said second device for holding said circuit-controlling means in actuated position.

26. In apparatus of the character described, in combination, a source of current, a work circuit supplied therefrom, regulating means for controlling a function of the energy supplied by said source to said work circuit, said regulating means including a plurality of devices, each having spaced electrodes between which electronic conduction is adapted to take place and each adapted to affect said regulating means, switching means interposed between successive devices and adapted upon actuation to cause a succeeding device to become connected to affect said regulating means, and means responsive to a predetermined rise in the function of the energy supplied by said source to said work circuit for actuating said switching means.

27. In apparatus of the character described, in combination, a source of current, a work circuit supplied therefrom, a carbon pile regulator for controlling a function of the energy supplied by said source to said work circuit, and means for controlling said carbon pile regulator, said means including two coils having opposed effects thereon and connected to be responsive to substantially the same changes in the function of the energy supplied by said source to said work circuit, and means having spaced electrodes between

which conduction takes place for causing one of said coils to have a greater responsiveness than the other.

28. In apparatus of the character described, in combination, a source of current, a circuit for receiving current therefrom, a carbon pile for controlling a function of the current supplied to said work circuit, two voltage responsive electromagnetic means, each responsive to the voltage across said circuit, the one acting in a direction to compress said carbon pile and the other acting in a direction to relieve compression of said carbon pile, and means having spaced electrodes between which electronic conduction may take place for causing one of said electromagnetic means to have a greater responsiveness than the other.

In testimony whereof, I have signed my name to this specification this 6th day of May, 1926.

ALAN VARLEY LIVINGSTON.
